UNITED STATES PATENT OFFICE.

LOUIS N. D. WILLIAMS, OF OGONTZ, PENNSYLVANIA.

UNITING KNITTED WEBS

1,194,802.

Specification of Letters Patent. Patented Aug. 15, 1916.

Application filed June 10, 1915. Serial No. 33,244.

To all whom it may concern:

Be it known that I, LOUIS N. D. WILLIAMS, a citizen of the United States, residing in Ogontz, Pennsylvania, have invented 5 certain Improvements in Uniting Knitted Webs, of which the following is a specification.

My invention consists of a novel method 10 of uniting the stitches at opposite sides of a knitted web, as, for instance, the stitches around the mouth of a toe pocket and those around the forward edge of the instep web of a stocking foot.

In the accompanying drawing—Figure 1 15 is a sectional view of sufficient of a circular knitting machine to illustrate the first step in the carrying out of the method in accordance with my invention; Fig. 2 is a similar view illustrating the second step in said 20 operation, and Fig. 3 is a sectional view illustrating the final step.

In Fig. 1 of the drawing, 1 represents part 25 of the needle cylinder of a knitting machine, within which is mounted a sliding tube 2 with a flange 3 at its upper edge. Upon this flange rests a semi-circular segment 4 having projecting points or quills 5 thereon, which are adapted to engage with stitches formed upon the needles 6 throughout one 30 half of the circumference of the needle cylinder, the segment 4 being disposed beneath the web produced upon these needles, and during the knitting of the web occupying the position shown by dotted lines in Fig. 1, 35 that is to say, with the points of the quills below those portions of the web holders over which the stitches are drawn.

When the stitches are to be transferred, a semi-circular segment 4^a, having down- 40 wardly pointing quills 5^a, is applied from above the web to stitches formed upon the needles 6^a extending around the other half of the cylinder, and the tube 2 is raised so that its flange 3 causes a lift of the segment 4 and the projection of the quills 5 of the same through the stitches upon the needles 6, as shown by full lines in Fig. 1. At the 45 same time the needles 6, 6^a are retracted so as to cast the stitches therefrom and the web 50 holders 7, 7^a are also retracted, as shown

in Fig. 2, so that the quill carrying segments 4 and 4^a are free to be lifted to the position shown in said figure. The segment 4 and its stitch-carrying quills is then folded over upon the segment 4^a so that the points 55 of the quills 5 overlap the bases of the quills 5^a, as shown by dotted lines in Fig. 2. The quill carrying segments, occupying the position shown by dotted lines in Fig. 2, and with the stitches upon them, are then applied to the carrier 8 of a looping machine to which an intermittent step by step movement is imparted so that the stitch forming needle 9 of the looping machine can successively engage the stitches carried by the 60 successive pairs of quills 5 and 5^a, the needle passing first through the stitch carried by the quill 5 and then through the stitch carried by the quill 5^a, or vice versa, as shown in Fig. 3. After this has been done the 65 quills 5 and 5^a are released from engagement with the stitches carried by them and the segments 4 and 4^a are removed from within the web.

In the drawing I have, for convenience, 70 shown but one of the quills of each of the segments 4 and 4^a and have shown only two needles, one at each side of the machine, as the showing in the distance of the quills of each segment and of the needles around half 75 of the circumference of the machine would tend to cause confusion.

My invention is not limited in its application to a circular knitting machine but can be applied as well to knitting machines having straight needle beds disposed back to back.

I claim:—

The mode herein described of uniting 80 stitches on opposite sides of a knitted web, 90 said mode consisting in first projecting stitch receiving quills through stitches on one side of the web from below said web and projecting stitch receiving quills through stitches on the other side of the web from above the 95 same, then folding one set of quills with the stitches upon them over into registry with the other set of quills, and causing the points of one set of quills to overlap the bases of the other set, and then uniting the pairs of 100

stitches upon the quills by means of a separately produced chain of stitches, the stitch forming needle passing first through a stitch on one of the quills and then through the 5 stitch on the quill which registers therewith.

In testimony whereof, I have signed my

name to this specification, in the presence of two subscribing witnesses.

LOUIS N. D. WILLIAMS.
